UNITED STATES PATENT OFFICE.

RICHARD E. HALL, OF CLEAN, NEW YORK, ASSIGNOR TO SEAMAN CONTAINER MFG. CO., OF CLEAN, NEW YORK, A CORPORATION OF NEW YORK.

PROCESS AND APPARATUS FOR REGULATING FEED AND DENSITY OF PULP TO A PULP-MOLDING MACHINE.

Application filed December 29, 1924, Serial No. 758,507. Renewed January 5, 1926.

This invention relates to improvements in process and apparatus for uniform pulping, and refers more particularly to the automatic regulation of the consistency of fibrous pulp solutions to automatically produce fibrous articles of uniform weight and density, when dry.

For many years, attempts have been made to discover the secret of so controlling the introduction of fresh fibrous pulp solution and the withdrawal for use of circulating pulp solutions so as to automatically control the weight and density of the dried fibrous products. These efforts have not been completely successful in their results, and my invention is directed to a solution of the problem.

The present invention is shown as used with the process and apparatus disclosed and described in co-pending application filed by me, Serial No. 744,586, filed October 20th, 1924, and to void complications of unnecessary detail, merely those details will be shown in the drawings and described in the specification, as are necessary for a clear understanding of the present improvement.

One specific embodiment of my invention may be described as follows:

Fibrous pulp of a given consistency is fed into a primary bulk supply having an overflow which controls the level of the pulp solution therein, and, therefore, the amount of pulp. At predetermined periods, the valve on the primary bulk supply may be automatically opened, and all or any part of the entire contents thereof may be discharged into a mixing tank from which it may flow preferably by gravity, to one end of the felting tank. From the opposite end of the felting tank the excess portions of the pulp solution may be withdrawn, preferably by means of a pump, and may be forced to the mixing tank. Flow of water into the mixing tank may be automatically governed by a float valve, serving to maintain a very nearly constant level in the felting tank.

By this arrangement, I am able to positively control the amount and weight of pulp introduced to the mixing and felting tanks from the primary bulk supply, as well as the amount of water introduced and simultaneously therewith, maintain a cyclic circulation of the pulp solution between the mixing and felting tanks.

The amount of fibrous pulp depositing on forms introduced to the felting tank depends chiefly upon the time and amount of suction, and the density of the pulp, but, is also affected by the nature of the fibre, temperature of the pulp and cleanliness of the screens. As all of these items vary, an automatic control is absolutely essential in obtaining articles of uniform weight when dry.

The advantages and novel features of the process and apparatus will be discussed in the following description.

Fig. 1 is an end elevational view, and Fig. 2 is a side elevational view, of apparatus for carrying out my invention.

Fig. 3 is a top plan view of same. Fig. 4 is a side elevational detail of the mechanism for automatically opening and closing the pulp solution supply valve.

Referring in detail to the drawings, 1 designates a primary bulk supply tank into which fibrous pulp of a given consistency is introduced. This tank preferably has a conically shaped bottom for more accurate regulation, although this is not essential. The tank 1 communicates through nipple 2 with the T 3 having open communication with pipe 4 which has swing joint 5, vertical overflow pipe 6, having outlet 7 discharging into trough 8. The arrangement is such that the overflow pipe 6 is adapted to be positioned at a predetermined angle to automatically regulate the level in the tank 1, and thereby accurately control the amount of pulp introduced. On the opposite side of the T 3 is an extension 9, in which is interposed the valve 10, the operation of which will be hereinafter explained. The pipe 9 discharges into the mixing tank 11, which preferably has a free communication by means of pipe 12 with the felting tank 13. On the opposite end of the felting tank 13, and preferably adjacent the lower part thereof, is the pump 14, communicating by means of the slanting riser 15 with the mixing tank 13. The conical tank 1 may be supported in any desired manner, for instance, by the supporting standards 16. Water may be introduced to the mixing tank 11 through the inlet 17 controlled by float valve 18 communicating by means of the lever 19 with the ball 20; it being understood that when the level in the tank 11 falls, the ball 20 will also fall and eventually

ally open the valve 18 to permit the introduction of water. The felting tank 13 may be connected with the stationary suction pipe 21 having the enlarged stationary connecting joint 22 which communicates with a suction header rotating in tank 13.

It must be understood that the broad principle of the present invention is adapted for use with any process or apparatus which 10 contemplates the production of felted fibrous articles.

The automatic functioning of the mechanism for opening and closing the valves may be described as follows: Projecting outwardly from the valve 10 is the stem 23, having a star wheel 24 fixedly keyed on its extremity, it being understood that the rotation of the stem will rotate the valve 10 to open or close same. On predetermined arms 25 which 20 as disclosed and described in detail in my co-pending application heretofore referred to, are radial extensions from the hub on the rotating wheel to the segmental plates 26, extending in a circular plane from the extremities of said arms 25 to a point short of contact with the next succeeding arm. Projecting from the surface of these plates 26, at substantially right angles thereto, are two pins 27 and 28. The arrangement is such 25 that as the connecting rod 29 is moved vertically in the guide 30, the hook on said connecting rod registers with studs on the arm 25 to pull same for a predetermined distance of rotation in an arc. When the arm 30 25 carrying the plate 26 and pins 27 and 28 is moved, the pin 27 contacts the star wheel 24 which opens the valve 10 to allow a regulated amount of pulp solution from tank 1 to be discharged into the mixing tank 11. It 35 is understood that the pin 27 is in movement at the time of contact with the star wheel and passes said star wheel. The continued movement of the arm 25 brings the pin 28 into contact with the star wheel 24 which causes 40 said star wheel to be rotated, for instance, a quarter turn, to close valve 10.

It is understood that the valve 10 may be 50 manually opened and closed, if desired, at predetermined intervals, after the number of pails have been produced, corresponding to the charge of wet pulp in tank 1, which is controlled in amount by the overflow 6. This overflow also regulates the amount of 55 pulp solution discharged into the mixing tank 11, when operated automatically, as the entire charge may be discharged into the mixing tank 11 during the time the valve 10 is open. In practice, it has been found that on account of the weight of pulp 60 solution in the bulk supply 1, and the force of gravity, the entire contents of tank 1 will be discharged during the time the valve 10 is open.

31 represents the chain which drives the mechanism for rotating the wheel on which

the felting forms are mounted. As a practical illustration of one manner in which the present invention is carried out in practice, may be cited the following: If it is desired to obtain pails having a uniform 70 weight, when dry, of say, two pounds, and the pins 27 and 28 are placed so as to discharge the conical tank 1, say, every fourth pressing, where there are eight felting forms on the wheel, the overflow pipe 6 is set so 75 that the conical tank 1 holds just eight pounds of dry weight pulp. (160 pounds wet weight of 5% pulp). As there is used about 1% pulp in the felting tank (that is, 80 1 part of pulp to 99 parts of water), it follows that between each discharge from tank 1 into mixing tank 11 through the valve 10, the float valve 18 and pipe 17 adds about 640 pounds of water. If the fibre is free 85 and warm, and the felting form screens clean (time and amount of suction being uniformly maintained), more water will be drawn through the foraminations of the form and a deposit of more than two pounds of fibre on each pail will be made. Thus, 90 the float valve 18 will be actuated by the level falling in tank 11 to add more water than usual to bring the level in tank 11 up to normal, which results in making the pulp less dense and the succeeding felted product will have less fibre deposited on it, and 95 it has been my experience in operation that the felted products soon come to two pounds and remain there with negligible variation.

On the other hand it has been found that 100 if the felting screens are partially clogged with dirt the fibre not free, etc., the suction will not withdraw as much water as usual, and there is less than two pounds of fibre deposited, then the float valve 18 adds less 105 water, the pulp becomes denser and although no increased amount of water is withdrawn by the suction, the felting forms will have more fibre deposited on it (through its increased density) and deposits more fibre on 110 the felting forms and the felted products return to two pounds weight.

I have given a specific illustration in the foregoing, but it is to be understood that I 115 do not in any way wish to limit myself except as set forth in the appended claims. In its broad aspects, the principle of the present invention, namely, the automatic regulation and maintenance of the introduction of pulp solution and the consequent 120 production of felted products of substantially uniform weight.

I claim as my invention:

1. A process of regulating feed and density of pulp to a pulp molding or felting machine, consisting in maintaining a primary bulk supply of pulp solution, automatically introducing at predetermined times pulp solution from the latter to a secondary bulk supply, substantially regulat- 130

- ing the introduction of water to said secondary bulk supply functioned by the level of pulp solution therein, withdrawing pulp solution from the secondary bulk supply and introducing same to a felting tank, returning excess portions of pulp solution from the latter to the secondary bulk supply, thus maintaining a cyclic circulation between the secondary bulk supply and the supply in the felting tank.
2. A process of regulating feed and density of pulp to a pulp molding or felting machine, consisting in maintaining a primary bulk supply of pulp solution, automatically introducing at predetermined times regulated amounts of pulp solution from the latter to a secondary bulk supply automatically regulating the introduction of water to said secondary bulk supply functioned by the level of pulp solution therein, continuously withdrawing pulp solution from the secondary bulk supply and introducing same to a felting tank, continuously returning excess portions of pulp solution from the latter to the secondary bulk supply, thus maintaining a forced cyclic circulation between the secondary bulk supply and the supply in the felting tank.
3. A process of regulating feed and density of pulp to a pulp molding or felting machine, consisting in maintaining a primary bulk supply of pulp solution, automatically introducing at predetermined times regulated amounts of pulp solution from the latter to a secondary bulk supply, automatically regulating the introduction of water to said secondary bulk supply functioned by the level of pulp solution therein, continuously withdrawing pulp solution from the secondary bulk supply by gravity, and introducing same to a felting tank, continuously returning excess portions under forced pressure, of pulp solution from the latter to the secondary bulk supply, thus maintaining a forced cyclic circulation between the secondary bulk supply and the supply in the felting tank.
4. A process of automatically regulating the consistency and density of fibrous pulp solutions, consisting in maintaining a primary bulk supply of pulp of known controlled consistency, maintaining a predetermined level in said primary bulk supply, automatically discharging at predetermined times the pulp to a secondary bulk supply, introducing water to the latter, automatically regulating the introduction of said water by the level in said secondary bulk supply, introducing pulp solution from the latter to a felting zone in which a body of pulp solution is maintained, felting portions of the pulp in the latter, returning excess portions to said secondary bulk supply, thus maintaining a cyclic circulation between the felting zone and secondary bulk supply.
5. A process of automatically regulating the consistency and density of fibrous pulp solutions, consisting in maintaining a primary bulk supply of pulp solution of known controlled consistency, maintaining a predetermined liquid level in said primary bulk supply, automatically discharging at predetermined times the entire content of pulp solution to a secondary bulk supply, introducing water to the latter, automatically regulating the introduction of said water by the level in said secondary bulk supply, continuously introducing pulp solution by gravity from the latter to a felting zone in which a body of pulp solution is maintained, felting portions of the pulp in the latter, continuously returning excess portions under forced pressure to said secondary bulk supply thus maintaining a continuous forced cyclic circulation between the felting zone and secondary bulk supply.
6. In apparatus for regulating feed and density of pulp to a pulp molding or felting machine, the combination with means for maintaining a primary bulk supply of pulp, means communicating therewith for maintaining a secondary bulk supply having water inlet, means for controlling the liquid level in said secondary bulk supply functioning to automatically regulate the introduction of water, valve mechanism interposed between the primary and secondary bulk supply, a felting zone having communication with the secondary bulk supply, means communicating between the latter, for returning excess portions from the felting zone to the secondary bulk supply.
7. In apparatus for regulating feed and density of pulp to a pulp molding or felting machine, the combination with means for maintaining a primary bulk supply of pulp, having overflow means communicating therewith for maintaining a secondary bulk supply having water inlet, means for controlling the liquid level in said secondary bulk supply functioning to automatically regulate the introduction of water, valve mechanism interposed between the primary and secondary bulk supply, a felting zone having communication with the secondary bulk supply having a pump for returning excess portions from the felting zone to the secondary bulk supply under pressure, and means for automatically opening the valve mechanism at predetermined times to discharge pulp from the primary bulk supply into the secondary bulk supply.
8. In apparatus for regulating feed and density of pulp to a pulp molding or felting machine, the combination with means for maintaining a primary bulk supply of pulp, means communicating therewith for maintaining a secondary bulk supply having water inlet, means for controlling the liquid level in said secondary bulk supply func-

tioning to automatically regulate the introduction of water, valve mechanism interposed between the primary and secondary bulk supply, a felting zone having communication with the secondary bulk supply, means communicating between the bulk supply, for returning excess portions from the felting zone to the secondary bulk supply, and means for maintaining a forced circulation between the felting zone and said secondary bulk supply.

9. A process of regulating density and feed of pulp to a felting machine, comprising maintaining a primary bulk supply of pulp solution, in introducing at predetermined times pulp from the latter to a secondary bulk supply, regulating the introduction of water to said secondary bulk supply, withdrawing pulp solution from the secondary bulk supply and introducing same to a felting tank and returning excess of pulp solution from the felting tank to the secondary bulk supply, thus maintaining a cyclic circulation between the secondary bulk supply and the supply in the felting tank.

10. A process of regulating density and feed of pulp to a pulp molding or felting

machine, comprising maintaining a primary bulk supply of pulp solution, introducing at predetermined times pulp solution from the primary bulk supply to a secondary bulk supply, automatically regulating the introduction of water to said secondary bulk supply, withdrawing pulp solution from the secondary bulk supply and introducing same to a felting, or molding tank, returning excess pulp solution from the latter to the secondary bulk supply, thus maintaining a cyclic circulating between the secondary bulk supply and the supply in the felting tank.

11. A process of regulating density and feed of pulp to a pulp molding or felting machine, comprising maintaining a primary bulk supply of pulp solution, automatically introducing pulp solution from the primary bulk supply to a secondary bulk supply, automatically regulating the introduction of water to said secondary bulk supply functioned by the level of pulp solution therein, withdrawing pulp solution from the secondary bulk supply and introducing same to a felting or molding tank.

RICHARD E. HALL.
